UNITED STATES PATENT OFFICE.

MALCOLM F. EWEN, OF CHICAGO, ILLINOIS, ASSIGNEE TO CENTRAL TRUST COMPANY OF ILLINOIS, TRUSTEE, OF CHICAGO, ILLINOIS, A CORPORATION OF ILLINOIS.

APPARATUS FOR ADMINISTERING ANESTHETICS OR ANALGESICS.

1,256,481.

Specification of Letters Patent. Patented Feb. 12, 1918.

Application filed April 29, 1916. Serial No. 94,316.

To all whom it may concern:

Be it known that I, MALCOLM F. EWEN, a citizen of the United States, and a resident of Chicago, in the county of Cook and State 5 of Illinois, have invented certain new and useful Improvements in Apparatus for Administering Anesthetics or Analgesics; and I do hereby declare that the following is a full, clear, and exact description thereof, reference being had to the accompanying drawings, and to the letters of reference marked thereon, which form a part of this specification.

This invention relates to an apparatus for 15 administering anesthetics or analgesics and consists of the matters hereinafter described and more particularly pointed out in the appended claims.

The invention relates more particularly 20 to improvements in the form of apparatus shown and described in an application for Letters Patent heretofore filed April 3rd, 1915, by Will P. Walter, Serial Number 18,868, relating to an apparatus for administering anesthetics and is primarily intended for use in connection with such operations where chloroform, ether or the like is not required and only gases or vapors forming an analgesic mixture are necessary.

The object of the invention is to simplify 30 the form of the apparatus; to provide an improved and more easily readable form of sight feed gage device to determine the proportions of the gases in the analgesic or anesthetic mixture; to provide an improved device whereby the said proportions may be 35 preliminarily determined and whereby the flow of gases forming the mixture may thereafter be controlled by a member operable by one hand; to provide means for preventing an excess of pressure above a certain low pressure from being brought to bear upon the lungs of the patient; and to provide improved connections whereby the 40 gas cylinders of different lengths are made capable of attachment to the apparatus.

These and various other objects and advantages of my invention will appear more clearly as I proceed with my specification.

Referring now to the drawings:

Figure 1 is a view representing my improved apparatus in front elevation with the gas or vapor cylinders connected thereto.

Fig. 2 is a view representing the same in 55 side elevation.

Fig. 3 is a view representing a vertical

section of the apparatus in a plane indicated by the line 3—3 of Fig. 2.

Fig. 4 is a top plan view of the apparatus with the cap or cover removed.

Fig. 5 is a view representing a partial vertical section through one of the sight feed tubes of the apparatus.

Fig. 6 is a view representing a vertical section through the other sight tube of the 65 apparatus.

Fig. 7 is a view representing a vertical section through the apparatus in a plane indicated by the line 7—7 of Fig. 1.

Fig. 8 is a view representing a transverse 70 section through the apparatus in a plane indicated by the line 8—8 of Fig. 7.

Referring now to that embodiment of my invention illustrated in the drawings:—10 75 indicates a casing, preferably made of metal, which provides a support for a head 11, that contains the valve mechanism of the improved device, and that also has attached to it the yokes 12, by means of which the gas or vapor cylinders which supply the constituents for the analgesic or anesthetic mixture, are connected to the device. The said casing also provides a protecting closure for a transparent vessel or jar 13 in which are located upright transparent sight feed gage 85 tubes 14, 14^a. This jar contains the water or other washing fluid by means of which the gases or vapors forming the anesthetic mixture are washed before being administered to the patient.

As shown, the casing 10 is a tubular, substantially rectangular shell which is open at the top and which has a bottom wall 15. It is preferably provided with an open base 16 having a plurality of spaced foot pieces 17 95 made of elastic material such as rubber or the like, to prevent the metal of the casing from marring or scratching a table or desk upon which the apparatus is placed.

The transparent vessel 13 consists of a 100 glass tube which as shown is of cylindric form and is of such diameter as to fit easily within the casing 10. Said tube is closed at the top and bottom respectively by means of elastic disks or gaskets 18, 19, made of 105 rubber or other like material. The head 11 is a plate which closes on the elastic disk covering the top of the glass tube 13 and which is attached to inwardly projecting ears 22 formed at the top of the casing 10, 110 by means of screws 23. By means of said screws, manifestly the head may be drawn

down upon the casing 10, so as to tightly seal the ends of the transparent tube 13 against the elastic disks 18 and 19 at the bottom and top respectively of said tube.

5 The sight feed gage tubes 14, 14^a are each preferably made in two parts, a bottom part 14^x of glass or other suitable transparent material, and a top part 14^y of metal. An annular elastic washer 14^z is interposed between the two parts and each tube as a whole is sealed at top and bottom by means of annular bosses, 24, 25, formed respectively upon the top and bottom disks or gaskets 18, 19. The ends of said tubes are depressed 10 into the elastic material forming the said gaskets and the abutting ends of the two parts of each tube are tightly engaged against the interposed washer when the head 11 is drawn down upon the casing, so 15 that the sight feed gage tubes like the larger outer tube 13, are securely sealed against leakage. A recess 26 is formed in the bottom wall 15 of the casing 10 connecting points below the two sight feed gage 20 tubes and the said sight feed gage tubes are connected with the interior of the larger tube 13 by means of passages 27, 27, opening from the sight feed gage tubes into the recess 26, and a passage 28 connecting said 25 recess with the interior of the larger tube 13.

There is provided on the head 11 an upright boss 29, in which are formed two 30 valve casings 30, 30,—one associated with each sight feed gage tube. Each valve casing opens by means of a passageway 31 extending through the top gasket 18 into its associated sight feed gage tube. Each valve casing contains a needle valve 32 that controls the flow through said passage 35 31 from a passage 33 that is connected by means of a hand-controlled shut-off or pet 40 cock valve 34 to the usual nipple 35 of the yoke 12 which is adapted to be connected to the neck of the gas or vapor cylinder in a 45 familiar manner.

Pressure reducing valves 36 are interposed between the nipples 35 and the valves 34, said reducing valves being connected by brackets 37, 38, respectively, to the yokes 12 50 and to the head 11. The valve plug of each pet-cock valve 34 is adapted to be rotated by means of a radial arm 39, and the arms of the two valves are connected by links 40 to a horizontal operating lever 41 fixed upon 55 an upright shaft or pin 42 having rotative bearing in the boss 29 and being provided with a handle 43 for rotating it. The arms 39 and links 40 of the two valves are so disposed relatively to the lever 41, as clearly 60 illustrated in Fig. 4, that the two valves will be opened or closed by the same rotative movement of the shaft or pin 42.

The yokes 12 consist of open rectangular frames arranged in a plane which is disposed at an angle to the horizontal, and

which is made of such lateral dimensions that the necks 44 of the gas cylinders 45 may be engaged therein and still rest with their bottom ends on the support upon which the casing 10 rests; that is to say, these yokes 70 are so constructed as shown, that the cylinders may be inclined at different angles, as illustrated in Fig. 2, of the drawings, without interfering with the proper engagement of their necks within the yokes. The outer 75 end members 12^a of the yokes 12 have threaded through them the familiar clamping screws 12^b located in axial alinement with the nipples 35 and adapted to securely clamp the neck of the gas cylinders in gas 80 tight engagement with the nipples.

From the construction thus far described, it will be apparent that the pressure of the gas escaping from the cylinders may be reduced by means of the reducing valves 36, 85 so that the apparatus will not be subjected at any time to any great pressure. Thus, whether the gas cylinders are full or only partially filled, the pressure induced in the apparatus will always be low. 90

The valves 34 are mere shut-off valves, but the valves controlled by the needles 32 are adjustable to determine the flow of gas from said shut-off valves to the sight tubes 14, 14^a. Thus, manifestly, by adjusting the 95 opening of the valves 32 relative, the one to the other, a proportionate rate of flow of the gases from the two shut-off valves may be carefully predetermined.

The jar 13 is filled in a manner presently 100 to be described with the washing liquid up to a certain level, for example, that shown in the drawings. When no gas is flowing into the sight feed gage tubes 14, 14^a, the liquid will stand at the same level in the 105 jar and in the tubes, since said tubes are connected to the jar by the passageway provided by the recess 26 in the bottom wall of the casing 10. When gas is admitted into the sight feed gage tubes 14, the pressure of the 110 gas will act to depress the level of the water in the tubes, below the level in the vessel 13, part of the liquid in said tubes being forced out through the passage 27, the recess 26 and the passage 28 into the jar 13. It will 115 be manifest that the relative amount of depression in the two sight feed gage tubes will be in direct proportion to the head or pressure under which the gases enter said tubes. 120

Each of the tubes is provided with outlet openings, 14^b, 14^c, respectively, for the escape of gas to the vessel 13. Said openings are located below the normal level of the washing liquid in the said vessel 13; said 125 openings are made in the metal part of each tube and it is on account of the difficulty of making these openings, or apertures in glass that the tubes are made in two parts (metal and glass) as described. Preferably 130

but one opening, or aperture, 14^b is provided in the tube 14, which as shown, is connected with the oxygen side of the apparatus, while a plurality of openings, or apertures, 14^c (3 as illustrated) are provided in the other (nitrous oxid) tube. The outer end of the single opening, 14^b, in the tube 14, is countersunk or flared as shown in Fig. 5, to prevent capillary attraction from obstructing 10 the free escape of the gas or vapor from the tube. This construction is not necessary in the openings of the other tube, 14^a, from which the flow of gas is greater in volume and wherein the openings have straight 15 sides, as indicated in Fig. 6.

The gas entering into the tubes 14, 14^a, escapes below the level of and into the body 20 of the liquid contained in the jar 13, and thence bubbles up into the space above the level of said liquid. From there it escapes 25 through a passage 46, provided in the boss 29 of the head 11, which passage extends upwardly and then continues forwardly and outwardly through a nipple 47 formed at the front of the head (see Fig. 7). Said 30 nipple is adapted to be connected with the tube leading to the face or mouth appliance or other device by means of which the gas mixture is to be administered to the patient in a familiar manner. As the friction 35 to which the gases are subjected in their passage through the apparatus to the nipple 47 is substantially the same in the case of both gases, the amount of gas in the mixture 40 will be substantially proportional to the relative pressures induced in the said sight feed gage tubes and in proportion to the cross sectional area of the orifices 14^b, 14^c, through which they escape from the said tubes. 45 Thus, with the relative cross sectional areas of the openings 14^b 14^c, fixed (in the apparatus as illustrated in the relation of 1 to 3) the levels of the liquid in the said tubes may be used as a gage to determine the proportions of the gases in the anesthetic mixture. 50 For example, in the apparatus illustrated, if the liquid in the two tubes is depressed (by the adjustment of the needle valves 32) to the same level the proportion of the gases in the mixture will be 1 to 3. If the valves 55 were adjusted so that the liquid in the tube 14 is depressed one-half as much below the level of the liquid in the vessel 13 as it is depressed in the tube 14^a, the proportions of the gases in the mixture will be as 1 to 6.

In addition the amount of depression of the liquid in the sight feed gage tubes below the level of the vessel 13 will determine the head and the rate of flow; that is to say, 60 a greater depression of the liquid in the sight feed gage tubes will determine a greater flow of the mixture, while a lesser depression in the sight feed gage tubes will determine a lesser flow. Thus, manifestly, these tubes 65 provide means for visually or optically de-

termining not only the proportion of gases in the mixture but also a greater or less flow of the mixture.

I provide a card 48 which as shown, is graduated and which may be provided with 70 any suitable indicia in order to indicate the relative proportions of the gas pressures in the mixture when the liquid is depressed in the tubes to certain indicated levels.

With this card may be used a separate 75 index which may be carefully worked out and which will indicate that in order to get a certain desired proportion of each gas in the anesthetic mixture, the level in one tube will have to be depressed to one point on the 80 gage, whereas the other will have to be depressed to another point on the gage.

The casing 10 has a wide vertically elongated opening 10^a in its front wall (see Fig. 1), to disclose the sight feed tubes 14, 14^a, 85 and the associated card 48 to view. If desired the liquid and card may be given contrasting colors so as to make the reading of the scale on the card and the levels in the tubes 14, 14^a more quickly and easily determinable. 90

In using the apparatus, the hand valves or pet-cocks 34 are both opened wide and the needle valves 32 are each adjusted until the level of the liquid in the associated tube 14 95 is brought to the required number or index mark on the card to produce the mixture having the two gases in the desired proportion. The hand-valves 34 are then closed and the apparatus is ready for use. The 100 mask is then applied to the patient in the usual fashion and all that is necessary to do is to open the hand valves by means of the common operating member 43 and the mixture will then be delivered from the apparatus with the two gases in the proportions which were determined by the adjustment 105 of the needle valves in the first instance.

An upright screw or pin 57 (see Figs. 4 and 7) is fixed to the head 11 in position to 110 strike the lever 41 and limit the movement of said lever and consequently of the operating member 43, in closing the shut-off valves. This prevents the operating parts from being thrown upon a dead center. The 115 head 11 is inclosed by a tubular cap 11^x, which has suitable apertures through which the needle valve stems 32 and the operating shaft or pin 42 project. Thus the several valves may be operated as described without 120 removing said cap. The side walls of said cap also have suitable apertures for the parts of the apparatus which extend laterally beyond the head.

The washing liquid is admitted into the 125 glass vessel through a tube 49 fixed in the head 11 and depending through an aperture in the head into said vessel.

The tube 49 depends into a comparatively larger tube 51 which is arranged upright 130

within the jar 13 and is fixed to and rises from the base 15 of the casing 10. The said tube 51 rises nearly to the top of the jar and has a closed bottom wall 52. The construction described forms a seal. When the washing fluid is poured into the tube 49 it will fill the tube 51 and, rising in the tube, overflow into the glass jar. This may be continued until the liquid is raised to the desired level in the glass jar. The air or other gas within the jar escapes through the passage 46 and the nipple 47 in the filling of the jar. After the jar has been filled to the desired level, there still remains the liquid 10 in the tube 51, which extends to a level above the level of the water in the vessel, or glass jar. A tube 50 is fixed to the top of the tube 49 and extends a certain distance above the top of the apparatus. This tube is preferably made with a flange 50^a at its bottom end, which has somewhat larger diameter and is adapted to be slipped upon the top of the tube 49. The tube 49 has a constricted opening 49^a at its bottom end of somewhat 20 smaller diameter than the internal diameter of the tube itself, and an upright tube 49^b is fixed in said opening, said tube rising to a point shortly below the top of the large tube 51. This construction provides a blow-off 25 which is adapted to prevent the anesthetic gas from being administered to the patient at a pressure higher than a determined amount, namely, the pressure required to overcome the head represented by the difference 30 in level of the washing liquid in the tube 51 and the level of said liquid in the glass vessel and the additional pressure required to lift the differential column above the top end of the tube 50. Thus, if for any 35 reason, the gas pressure rises in the passage through the tube to the patient's mouth or nose to a point above the determined pressure under which the apparatus is designed to work, that is to say, a pressure greater 40 than the amount required to lift the said differential column of liquid in the tubes 49-50, this pressure will back up in the jar, or glass vessel, and act to force the liquid out through the tubes 49-50 and then into 45 the open air, through a restricted aperture 50^b at the top end of the tube 50, thus relieving the pressure within the jar and preventing the gas to the patient being anything 50 above the determined pressure.

55 The use of the small inner tube 49^b fixed in the constricted opening 49^a at the bottom of the tube 49, prevents the seal forming liquid from being forced, or driven, in a great quantity from the vessel in case the 60 pressure within the glass jar, or vessel, rises above the determined point.

To heat the gaseous or vaporous mixture, an electric heating unit 55 of any familiar construction is mounted in a suitable inverted tubular cup recess 56 (see Fig. 7)

fixed in the bottom wall 15 of the casing 10. This unit heats the washing liquid, which in turn, warms the mixture forming gases or vapors as they pass through it.

In order to drain the washing liquid from the jar 13, whenever or for whatever purpose required, a drain cock 58 is fixed to the bottom wall of the casing 10. A passage-way 59 is formed in said bottom wall and connects said cock with the recess 26, heretofore described as being connected with the interior of the tubes 14 and with the interior of the jar 13.

The graduated scale card or plate 48 is arranged in the vertical plane of the front of the sight feed tubes 14-14^a and said plate has its lateral upright edges bent to form arcuate wings or flanges 48^a-48^a which embrace or inclose approximately two-thirds of the circumferential area of said tubes, so as 85 to expose only the front sides of said tubes to view. Said plate 48 is fixed at its top end to the metallic sections 14^x-14^y of said sight feed tubes 14-14^a and its arcuate wings or flanges 48^a prevent buckling of the 90 tube sections at the gasket or washer 14^x under the downward pressure exerted thereon when the head 11 is secured in place as before described.

Should it be desirous at any time to administer either of the gases forming the anesthetic mixture, separately, to the patient, the handle 43 may be turned to close the valves 34-34 and the tube leading to the face mask or inhaler removed from the nipple 47 and connected to the nipple of either of shut-off valves 60-60 carried by the pressure reducing valve 36-36, said valves 60-60 of course communicating with the low pressure side of said reducing valves 105 36-36. The valves 60-60 are normally closed valves which may be readily opened to feed either gas to the patient, according to the needs arising from the conditions of the patient. As is apparent, this change 110 may be made from a mixed gas to either separate gas and vice versa without disturbing the proportions of the mixed gases provided for by the adjustment of the valve stem 32.

The operating member 43 of the stem 42 not only affords a means whereby the valves 34-34 may be operated simultaneously but also affords a very convenient handle by means of which the apparatus as a whole 120 may be carried or moved about. The head 11 as will be apparent from the foregoing description, carries all of the valves used in the apparatus. This construction is advantageous in that it increases the practicability 125 of assembling or cleaning of the parts without disturbing adjustments.

In the use of the apparatus, it may become necessary to renew or replace either one or both of the gas cylinders while the 130

anesthetic or analgesic fluid is being administered. The improved apparatus is of particular advantage at this time.

The natural and expected thing to be done 5 when a gas cylinder is to be replaced or renewed, would be to close the main shut off valves operated by the handle 43. Under these conditions the mixture, with the determined portions of the two gases, would 10 be administered to the patient under the gradually diminishing head due to the fact that the flow of gas from the two gas cylinders is stopped. This would be of no moment, however, as the time required in re- 15 placing the cylinder, or cylinders, would be but short. It may happen, however, that the attendant, by oversight or on account of attention to other matters, may fail to operate the handle 43 to close off the shut off 20 valves from the gas cylinders. It is under such circumstances that my improved apparatus operates at a special advantage. Thus, supposing that with the said shut off valves 25 still open one of the gas cylinders is disconnected. This leaves the reducing valve 36 associated with that gas cylinder open to the atmosphere. This will be of no moment, except for the escape of the gas in the line between the inlet of the reducing valve and 30 the top of the liquid level in the associated sight feed tube to reduce the pressure in said line to atmospheric pressure. Any further escape of gas would be prevented by the liquid in the vessel 13 and in the sight 35 feed tube. There would simply be a restoration of the balance of pressure between the liquid in the vessel and the liquid in the tube, and the liquid in the tube and in the vessel would form a seal to prevent the escape 40 of the mixture from the vessel.

Another advantage of the apparatus arises from the fact that the valves on the gas cylinders are apt to leak, no matter how tightly they are closed off. In the improved apparatus, if such leakage occurs, it will be immediately detected, since it will be evidenced by the depression in the associated sight feed gage tube.

While in describing my invention, I have 50 referred to certain details of mechanical construction and arrangement of parts, I do not wish to be limited thereto except as may be pointed out in the appended claims.

I claim as my invention:—

55 1. In an apparatus of the kind described, a closed vessel having a transparent wall, tubes located in said vessel back of said transparent wall, said tubes being two-part tubes and one of said tube parts being transparent, means closing the top and bottom ends of said tubes and means connecting the interior of said tubes with the interior of said vessel so that a liquid contained in the vessel will normally stand at the same level 60 in said vessel and in said tubes, openings in

said tubes below the level of said liquid, means adapted to connect each of said tubes with a source of gas or vapor supply, each of said connecting means including a valve for adjusting the pressure of gas introduced 70 by it, and means whereby the relative level of the liquid in said tubes below the level of the liquid in said vessel may be determined.

2. In an apparatus of the kind described, 75 a closed vessel having a transparent wall, tubes located in said vessel back of said transparent wall, said tubes being two-part tubes, and one of said tube parts being transparent, means closing the top and bottom ends of said tubes and means connecting the interior of said tubes with the interior of said vessel so that a liquid contained in the vessel will normally stand at the same level in said vessel and in said tubes, openings 80 in said tubes below the level of said liquid, means adapted to connect each of said tubes with a source of gas or vapor and for adjusting the pressure of gas introduced 85 by it, means whereby the relative level of the liquid in said tubes below the level of the liquid in said vessel may be determined, and an index card associated with said tubes and visible through the transparent wall of said vessel, said index card being adapted for indicating the relative levels of the liquid in 90 said tubes below the level of the liquid in said vessel.

3. In an apparatus of the kind described, 100 in combination with a sight feed gage device including tubes having transparent parts, means inclosing said tubes and a body of liquid normally standing at the same level in said tubes and inclosing means, means connecting said tubes with a source of gas 105 or vapor supply, said means including adjusting valves adapted to regulate the pressure of the gas or vapor admitted to the tubes and shut off valves to control the admission of gas or vapor to said tubes, and a 110 single controlling means adapted to simultaneously operate the several shut off valves associated with said tubes.

4. In an apparatus of the kind described, 115 in combination with a sight feed gage device including tubes having transparent parts, means inclosing said tubes and a body of liquid normally standing at the same level in said tubes and inclosing means, means connecting said tubes with a source of gas 120 or vapor supply, said means including adjusting valves adapted to regulate the pressure of the gas or vapor admitted into the tubes and shut off valves intermediate said adjusting valve and said source of gas or 125 vapor supply, and a single controlling means adapted to simultaneously operate the several shut off valves associated with the said tubes.

5. In an apparatus of the kind described, 130

in combination with a sight feed gage device including several tubes having transparent parts, means inclosing said tubes and a body of liquid normally at the same level
5 in said tubes and in said inclosing means, means connecting said tubes with a source of gas or vapor supply, said connecting means including adjusting valves adapted to regulate the pressure of the gas or vapor
10 admitted into the tubes, shut off valves to control the admission of gas or vapor to said tubes, and a reducing valve intermediate said shut off valve and said source of gas supply, and a single controlling means
15 adapted to simultaneously operate the several shut off valves associated with said tubes.

6. In a device of the kind described in combination with a closed vessel having a
20 transparent wall, parallel upright tubes closed top and bottom fixed in said vessel, said vessel and tubes containing a liquid, means connecting said tubes and vessel so that the liquid will normally stand at the
25 same level in said vessel and in said tubes and each tube being provided with one or more gas discharge openings below the normal liquid level therein, one of said openings being of large diameter at its outer end and
30 reduced in diameter at its inner intermediate end to eliminate capillary attraction.

7. In an apparatus of the kind described, a sight feed gage apparatus including a head, valves in said head and means for supporting said head, yokes adapted for the attachment of the necks of gas or vapor cylinders to said head, said yokes being substantially wider than the necks of said cylinders, and being fixed to said head in planes inclined to the vertical whereby the said cylinders may be adjusted at different angles when their necks are engaged in said yokes.

8. In an apparatus of the kind described, a tubular open top metal casing having a
45 base and a bottom wall and being provided with a view opening, a tubular transparent vessel located within said casing, tubes including transparent parts fixed in an upright position within said tubular vessel in line
50 with said view opening, said tubes being provided with gas delivery orifices, gaskets at the top and bottom of said vessel, a head closing the top of said casing, means for securing said head to said casing whereby
55 said tubes and said tubular transparent vessel may be drawn up gas tight upon said gaskets, the bottom wall of said casing being provided with a recess located below said transparent tube parts and the bottom gasket being provided with openings connecting said recess with said tubes and with the interior of said vessel.

9. In an apparatus of the kind described, a tubular open top metal casing having a bottom wall and being provided with a view opening, a tubular glass vessel located within said casing, tubes having transparent parts located within said tubular vessel in line with said view opening, said tubes being provided with gas delivery orifices, gaskets at the top and bottom of said vessel to close the top and bottom ends of said tubes and vessels, a head closing the top of said casing, means for securing said head to said casing, said head being provided with bosses to 75 form valve casings and inlet and outlet conduits, valve stems in said boss projecting above said head and a cap inclosing said head and provided with openings through which said valve stems project. 80

10. In a device of the kind described, in combination with a vessel having a transparent wall and sight feed gage tubes contained therein, said vessel and tubes containing a liquid, means for introducing gas under pressure into said tubes for escape from said vessel above the level of said liquid, and means providing a liquid seal, closing said vessel and adapted to be broken when the pressure in said vessel exceeds a 90 certain amount.

11. In a device of the kind described, in combination with a vessel having a transparent wall and sight feed gage tubes contained therein, said vessel and tubes containing a liquid, means for introducing gas under pressure into said tubes for escape from said vessel above the level of said liquid, means for fixing the maximum pressure to be attained in said vessel, consisting of a stand-pipe within said vessel open at the top, and a tube depending into said stand-pipe and communicating with the atmosphere outside said vessel, said tube and said stand-pipe providing a liquid seal for said vessel 105 and providing a head to determine the pressure that may be attained in said vessel.

12. In a device of the kind described, in combination with a vessel having a transparent wall, sight feed gage tubes contained therein and a liquid in said vessel and in said sight feed gage tubes, and means contained within said vessel for heating the liquid therein, whereby the gas or vapor escaping from said tubes may be heated on its way to 110 discharge from said vessel.

In testimony, that I claim the foregoing as my invention I affix my signature in the presence of two witnesses, this 27th day of April A. D. 1916.

MALCOLM F. EWEN.
